CLAIM

The ornamental design for a skimmer basket, as shown and described.

DESCRIPTION

FIG. 1 is a top perspective view of a skimmer basket, showing our new design;

FIG. 2 is a top perspective view thereof, showing a handle of the skimmer basket apart from the body of the same;

FIG. 3 is a bottom perspective view thereof;

FIG. 4 is a front elevation view thereof, the rear elevation view being mirror symmetrical thereto;

FIG. 5 is a right side elevation view thereof, the left side elevation view being mirror symmetrical thereto;

FIG. 6 is a top plan view thereof; and,

FIG. 7 is a bottom plan view thereof.

1 Claim, 7 Drawing Sheets
